UNITED STATES PATENT OFFICE.

PERCY W. SEAGER, OF LOS ANGELES, CALIFORNIA.

VALVE.

1,084,041.

Specification of Letters Patent. Patented Jan. 13, 1914.

Application filed May 9, 1913. Serial No. 768,693.

To all whom it may concern:

Be it known that I, PERCY W. SEAGER, a citizen of the United States, residing at the city of Los Angeles, in the county of Los Angeles and State of California, have invented new and useful Improvements in Valves, of which the following is a specification.

My invention relates primarily to a valve for that class of engine in which liquid hydrocarbon is commingled with air so as to form an explosive mixture which is exploded in the cylinders of the engine, and is primarily designed for use on an automobile, and the object thereof is to provide means when desired to supply an automatically regulated quantity of air into the manifold of an internal combustion engine between the carbureter and the cylinders and to thoroughly mix the air with the mixture passing through the manifold. I accomplish this object by the mechanism described herein and illustrated in the accompanying drawings forming a part hereof in which:

Figure 1 is a top plan of my device. Fig. 2 is a section on the line 2—2 of Fig. 1. Fig. 3 is a side elevation of my device with a part of the carbureter and a part of the manifold connected thereto. Fig. 4 is a section on the line 4—4 of Fig. 3.

In the drawings 5 is a cylindrical casing having a flange 7 at one end which when positioned for use is bolted to the carbureter 8. On the other end of the casing is a flange 9 which when positioned for use is bolted to the manifold 10. In the side of casing 5 is a port or opening 11 into which is received the inner end of a tubular casing 12 which forms a chamber for the reception and operation of the hollow manually operated tubular valve 13 and the automatic valve 14. Casing 12 is held positioned by a screw 15. Valve 13 is held in its adjusted position by a stud 16 which passes through a slot 17 in casing 12. An operating flexible wire 18 is secured to stud 16 by screw 19. Wire 18 passes through a flexible casing 20 and is connected to the operating lever 21 pivotally mounted on the base plate 22. Casing 20 is secured to base plate 22 and to a lug 23 projecting from casing 12. Base plate 22 has a row of depressions 24 into which is received a knob 25 which is mounted on lever 21 and holds said lever against accidental movement. This base plate is preferably fastened upon the steering post (not shown)

of the automobile. Casing 12 has ports 25 and 26 which are at different distances from its outer end and beyond the valve 13 when said valve is in its open position as shown in Fig. 2. The inner end of valve 14 is tapered and enters valve 13 and is normally held in contact with valve 13 to close the opening therethrough by spring 26 which is inclosed in the outer portion of casing 12. In a central hole 27 extending into valve 14 is received a lifting rod 28 which is pivotally mounted in lugs 29 secured upon swinging gate 30. Gate 30 is hinged to casing 5 on the carbureter side thereof and regulates the flow of the mixture from the carbureter. Opposite gate 30 is a screen 31 which is held supported and positioned by spider 32.

In the operation of my device when the maximum quantity of auxiliary air is desired valve 13 is set at its innermost position as shown in Fig. 2. Thereafter the greater the suction the greater the swing of gate 30 which moves valve 14 to uncover ports 25 and 26 and slot 17 thereby admitting the maximum amount of auxiliary air which commingles with the mixture from the carbureter in the central chamber of casing 5 and then passes through screen 31 which thoroughly mixes it and then on through the manifold to the cylinders. The less the suction the less the amount of auxiliary air admitted. By this device the admission of auxiliary air is automatically governed by the suction.

If a less amount of auxiliary air is desired valve 13 is moved to close so much of slot 17 and ports 25 and 26 as will permit the remaining portions to admit the amount of air desired. After being set at this point the action of admitting the air is automatic as before explained. When no auxiliary air is desired valve 13 is moved to entirely close slot 17 and ports 25 and 26. By this construction the amount of auxiliary air is manually regulated and its admission into the manifold is automatically regulated by the suction.

Having described my invention what I claim is:

1. An auxiliary air valve for explosion engines comprising a casing adapted to be positioned intermediate the carbureter and cylinders, said casing adapted to form a part of the manifold; a port in the wall of the casing; a valve chamber casing projecting into said port and secured to said casing,

said valve chamber casing having a longitudinal slot and a plurality of ports therein; a tubular valve in said valve casing for controlling said slot and ports; means to manually control the position of said valve; a second valve having a central hole extending into the body thereof in said valve casing adapted to close the opening through the tubular valve; a spring mounted in the valve casing to hold said second valve spring pressed upon the tubular valve; a swinging gate valve mounted to swing inwardly in the first mentioned casing; and a rod connected to said gate valve and extending through 10 the tubular valve and into the central hole of the said second valve.

2. In an explosion engine, a manifold having a channel therein, a swinging gate pro-

jecting across the manifold channel; a port adjacent to the hinge of said gate; a valve 20 casing surrounding and inclosing said port, said valve casing having a slot and ports therein for admitting air thereto; a manually operated tubular valve in said casing for controlling said slot and ports; an automatically operated valve to control the opening through the tubular valve; and means connected to the gate to operate said automatically operated valve.

In witness that I claim the foregoing I 30 have hereunto subscribed my name this 30th day of April, 1913.

PERCY W. SEAGER.
